INVENTOR

UNITED STATES PATENT OFFICE.

FRANK M. ASHLEY, OF NEW YORK, N. Y.

HORN.

Application filed February 9, 1926. Serial No. 86,999.

My invention relates to horns for use with radio receiving sets.

The object of my invention is to provide a horn which will transmit the tones of the reproducer without change except to increase the volume of sound.

A further object is to provide a horn which is so shaped as to be clearly moulded of plastic materials such as plaster of Paris or wax 10 compositions, or porcelain.

A further object is to provide an adjustable sound reflector which may be hinged to the body of the horn and held in adjustable position thereon to reflect and direct the sound 15 waves in the desired direction, and which may be adjusted vertically and at an angle to the vertical position, and also removable from the body of the horn so that reflectors of different forms and ornamental trimming 20 may be substituted to provide a choice for the purchaser.

Referring to the drawings which form a part of this specification:

Fig. 1 is a side elevational view of a horn 25 embodying my invention.

Fig. 2 is a front elevational view of the horn shown in Figure 1.

Fig. 3 is a cross sectional view taken on line 3—3 of Figure 2, looking in the direction 30 indicated by the arrows.

Fig. 4 is a side elevational view of another form of horn and reflector embodying my invention, the reflector being interchangeable with that shown in Figure 1, when constructed for sale.

Fig. 5 is a front elevational view of the horn shown in Figure 4.

Figure 6 is a cross sectional plan view taken on line 6—6 of Figure 5.

40 A, indicates a base portion which is preferably cast of metal and is formed hollow on its under side to receive the reproducer B, which is attached to a metal nipple C, which fits snugly in a cone-shaped hole A' formed 45 in the top of the base A. D, indicates the body portion of the horn made of plastic material, the lower end of which is firmly seated in the nipple C. The walls of the body portion are moulded to form wide face portions 50 and narrow side portions, and tapered from the bottom upward to provide a vase shaped horn having thick walls which may be embossed or ornamented on the face portions and may have handles D'—D' respectively at-

tached thereto formed of the same material 55 or of metal if desired.

This construction provides a body having a circular form of opening at the bottom which gradually changes into a rectangular or oblong form in cross section as it approaches 60 the top, such as illustrated in Figures 3 and 6, and also to provide a throat or bore that is fan-shaped.

Attached to each side near the top of the body portion D, are short metal shafts E—E which may be inserted in the mold and held by the material of the body portion in casting the body, or may be secured thereto by other proper means. The outer ends of these shafts 65 are threaded to receive the thumb nuts F—F 70 respectively.

Supported on the shafts E, are upwardly extending brackets G—G which support the sound reflector H. The sound reflector is preferably made of sheet or cast metal, but 75 may be made of plastic material if desired.

The reflector is formed to provide a hood which extends entirely across the top of the horn above the same at any adjusted distance therefrom within the movement of the supporting brackets, and is provided with short shafts I—I respectively located at each side thereof, which are threaded to receive the nuts I' by means of which the hood may be held in its adjusted position. By swinging 85 the brackets on the shafts, the hood may be raised or lowered and adjusted to the desired position, and held by the nuts in adjusted position. The hood may be formed in ornamental shapes and of materials having lustre 90 and pleasing color.

By making the hoods separable from the body portion, a number of different shapes may be provided to be interchangeable with body portions of different design from each 95 other, so that a line of horns of different ornamental designs may be provided with a minimum of expense for dies and molds. It is obvious that the horn may be used without the hood if desired.

100 The interior surfaces of the horn and the under side of the hoods should be formed smooth so that the sound waves will not be broken up in their transmission.

Having thus described my invention I 105 claim as new:

1. A sound amplifying horn having a body portion, a hood, brackets extending from the

- body portion to the hood and means for holding the hood in adjusted relation to the brackets and means for holding the brackets in adjusted relation to the body portion.
5. 2. A sound amplifying horn of the character described, comprising a body portion of plastic material having a small opening at its bottom end communicating with a bore of oblong form in cross section, a bracket connected to each side of the body portion in hinged relation thereto, and a hood carried between the brackets in adjustable relation to the top of said body portion and spaced therefrom.
10. 3. A sound amplifying horn of the character described, comprising a fan-shaped body portion of plastic material having a small opening at its bottom end communicating with a bore oblong in cross section, a bracket connected to each side of the body portion in hinged relation thereto and a hood supported entirely by the brackets above the top of the body portion at a distance therefrom.
15. 4. A sound amplifying horn comprising a vase-shaped body portion, a base portion, a bracket located at each side of the body portion, and a hood supported by said brackets mounted above the top of the body portion at a distance therefrom in hinged relation thereto.
20. 5. A sound amplifying horn of the character described, having a plastic body portion, a unitary hood, brackets connecting the hood at opposite sides only to the sides of the body

portion in hinged and adjustable spaced relation thereto, and means for holding the brackets in their adjusted position.

6. A sound amplifying horn having a moulded body portion, a unitary hood, side brackets connecting the body portion and hood and entirely supporting same at a distance above the top of said body portion in hinged adjustable relation thereto.

7. A sound amplifying horn comprising a plastic body portion, a unitary hood supported in hinged relation therewith at a distance therefrom, relative to the top of said body portion, and means for securing the hood in its adjusted position.

8. A sound amplifying horn comprising a base, an upright plastic body portion supported thereby, means extending above the body portion to support a hood, a unitary hood supported by said means and extending over and spaced from the top of the body portion in adjustable swinging relation thereto.

9. A sound amplifying horn having a body portion, a bracket hinged at each side of the body portion, a hood carried entirely by the brackets in swinging relation to and above the body portion, and means for holding the brackets in adjusted position.

Signed at New York city, in the county of New York and State of New York this 22nd day of September, A. D. 1925.

FRANK M. ASHLEY.
